UNITED STATES PATENT OFFICE.

HENRY ALLES, OF SAN FRANCISCO, CALIFORNIA.

TRAFFIC-SIGNALING DEVICE.

Application filed September 5, 1925. Serial No. 54,718.

My invention relates to traffic signaling devices and consists in arranging a signaling box having the words "Right", "Left" and "Stop" in the front and rear views of the box, and the letters "R", "L", and "S" in the ends of the box so as to be illuminated and shown through a red glass when the signals are given, and the hollow figure of a traffic officer is shown mounted on top of the box at the left side of the driver at the point where hand signals are looked for. The figure of the traffic officer raises the right arm, indicating right turn when it is desired to turn to the right, or the left arm when it is desired to turn to the left, or both arms when it is desired to stop. The signals given by the illuminated words and letters in the sides and ends of the box are in unison with those given by the hollow figure of the traffic officer mounted thereon, and the box is so mounted at the left side of the car as to be visible from the front, rear, and both sides, and the signals are plainly seen from in front through the glare of the headlights, thus preventing confusion. The words and letters in the sides of the signaling box are cut in the metal sides and are projected through red glass so as to indicate danger when the signals are given.

The box is divided into three signal lamp compartments, each having a lamp to illuminate through red glass the words and letters belonging to the respective compartments; and the mechanism to operate the arms of the figure and the electrical contacts is located in the top of the box.

The mechanism is shown operated from the steering wheel by a lever operating bell-crank which pull wires through armoured flexible tubing that are attached to bell-cranks within the signaling box. The bell-cranks within the signaling box are mounted pivotally to a bracket on the sides of the box and are attached to wires leading from the signaling box through the hollow body of the figure of the traffic officer to the pivoted arms, so that when a bell-crank is pulled it in turn pulls down the wires and raises the pivoted arm. Tension springs are attached to the wires and suitable bases which return the wires to their neutral position when the bell-cranks are released.

The bell-cranks, which are in the upper part of the signaling box and which are

actuated from the steering wheel, operate to close certain electric contacts in circuits leading to the lamps in said box. In so doing, the bell-cranks press upon insulators which are attached to spring leaf contacts, 60 which contacts are attached to conductor posts, thereby depressing the said spring leaf contacts into engagement with a lower spring leaf contact that is in circuit with an electric battery, whereby a current is caused 65 to flow through the circuit made by the contacts. In this way, when one of the dummy's arms is raised, a corresponding signal lamp is lighted.

There are three of these bell-cranks arranged side by side in the top of the signaling box. The two outer ones are attached to pulling wires leading through the armoured flexible tubing to the operating device shown at the steering wheel and the 75 middle one is attached to a wire leading through an armoured flexible tubing to the foot brake. When the bell-cranks shown at the steering wheel are thrown by the hand lever to one side the wire attached is 80 pulled and it in turn pulls the bell-crank in the signaling box, and in like manner pulls the wire to the pivoted arm of the figure of the traffic officer and raises the arm attached thereto and at the same time depresses the spring leaf to form a contact 85 with a charged spring leaf and causes a current to flow through the lamp which illuminates the proper signal.

The center bell-crank in the signaling box 90 is attached to a wire leading through an armoured flexible tubing to the foot brake and a tension spring, so that when the foot brake is depressed the tension spring pulls the wire leading to the central bell-crank 95 which has transverse metal leaves or bars attached thereto which engage the bell-crank on each side and depress both of them simultaneously, thus raising both pivoted arms of the figure of the traffic officer. 100 As the center bell-crank descends it strikes an insulator attached to the electrically charged spring leaf and begins to depress it before the bell-cranks upon the sides strike their insulators, and in this manner prevents electric contacts from being formed by the side bell-cranks and spring leaves while the continued depression of the electrically charged spring leaf makes a contact with a 105 spring leaf below it, and closes an electric 110

circuit leading to the lamp that illuminates the word "Stop". When the foot brake is released, the tension spring pulls the wire back into position and the circuit caused thereby is broken and the arms drop to a neutral position.

These and other features of my invention are more particularly described with reference to the accompanying three sheets of drawings, in which

Fig. 1 shows the traffic signaling device mounted upon the automobile by a hollow bracket leading to the signal box, through which the armoured flexible tubing holding the pulling wires pass to the signaling box. A side view of the figure of the traffic officer and an end view of the signal box is shown, also the operating device, which for convenience is shown below the steering wheel attached to the steering column and the armoured flexible tubings leading therefrom and from the foot brake into the hollow bracket are also shown together with the electric conductors to the signal lights.

Fig. 2 is a diagram of the electric conductors leading from the battery or generator to the signal lights.

Fig. 3 is a front view of the figure of the traffic officer mounted upon a base forming the top of the signal box and showing the connection of the wires which operate the arms to the bell cranks below. When the figure raises the right arm it indicates a right turn, the left arm indicates left turn and both arms indicate stop.

Fig. 4 is a longitudinal section through the signal box with a part of the back of the figure of the traffic officer cut out. It shows the wires connected to the bell cranks and from the bell cranks to the pivoted arms, also the electrical wiring and circuits to the signal lights. The signal box is divided into three signaling compartments, one for each lamp or signal—Right—Left—Stop and the letters R,—L, and S. The bell cranks are shown mounted to a bracket attached to the end in the top of the box. Also the tension springs and the electrical contacts consisting of spring leaves with insulators attached to the upper sides to prevent a short circuit when they are depressed by the bell cranks to make contact.

Fig. 5 is a side view of the figure of the traffic officer and an end view of the signal box with a portion cut away showing the bell cranks mounted on the opposite end of the box. This view shows the manner in which the leaves of metal are bent at right angles from the center bell crank to engage the bell crank on each side of the middle one, and depresses them with the center one when it is pulled down to signal "Stop."

Fig. 6 is a plan view of the spring and electrical connections which close the circuits to the various signals made by lamps

in the three compartments of the signal box.

Fig. 7 is an enlarged plan view of the means for operating the bell cranks.

Fig. 8 is a side view of Fig. 7.

Fig. 9 is a section through the operating mechanism contained in Fig. 7 and Fig. 8, showing the slot through which the operating lever engages the bell cranks, attached to pulling wires encased in armoured flexible tubing which is clamped in the lower end of the box. The lever slides in the slot to left or right and in forcing either bell crank over pulls upon the wire attached thereto.

In all the figures the same reference numerals refer to like parts.

Beginning with Fig. 9, the tip of the operating lever is shown at 1. When the lever is thrown to the right the point of the lever slides in the open slot to the left and engages the bell crank 2, which turns upon a pivot 85 and pulls the wire 3 shown at the bottom of the figure passing through an armoured flexible tubing held in clamps at the bottom of the box. The wire 3 leads through the armoured flexible tubing and the hollow bracket to the signal box to a screw clamp attached to a bar 39 having a slot in which is held a bell crank at 4, Fig. 4. When the bell crank 2 (Fig. 9) pulls the wire 3 it slips in the flexible tubing and pulls the slotted bar 39 and the bell crank 4, Fig. 4, which in turn pulls down the wire 5, Fig. 4, and raises the right arm of the figure of the traffic officer as indicated by the dotted lines of the arm. As the bell crank 4, Fig. 4, is pulled down, 100

it strikes on insulator 6 which depresses the spring leaf 7, and makes an electric contact with a charged spring leaf 8 and causes a circuit to flow through conductor 9 to the lamp 10 which shows through red glass and illuminates the word "Right" in the front and rear and the letter "R" on the ends of the signal box. When the operating lever 1 is thrown back to the central position at 1, Fig. 9, the bell crank is released and the coil spring 20, Fig. 4, pulls the wire 3 in the flexible tubing back to its original position and the tension coil spring 21 in the hollow body of the figure of the traffic officer pulls up the bell crank 4 and forces the arm from the dotted position shown in Fig. 4 down to the neutral position. This breaks the contact between the spring leaf 7 and the charged spring leaf 8, thus breaking the circuit to the lamp 10 and terminates the signal given for a right hand turn.

When it is desired to give a signal for a left hand turn the operating lever 1, Fig. 9, is pushed to the left which forces the bell crank 11, Fig. 9, over as the point of the lever 1 travels in the slot and pulls up on the wire 12, which is encased in an armoured flexible tubing leading to the signal box through the hollow bracket and is connected in a like manner to a bell crank 17, Fig. 3, 123

and is hidden behind 4, Fig. 4, to which is attached the wire 13 connected to the left arm of the figure, of the traffic officer and raises the pivoted arm to the position indicated by the dotted lines of the figure of the arm. In like manner the pull of the wire 12 upon the bell-crank 17, Fig. 3, Fig. 5, and Fig. 1, depresses upon an insulator 6 attached to spring leaf 18, Fig. 6, and makes a contact with the charged spring leaf 8 and sends a current through the conductor 14 which leads to the lamp 15 and the word "Left" upon the front and rear and letter "L" on the ends of the signal box are illuminated through red glass. By returning the operating lever 1, Fig. 9, to central position a coil spring 20, Fig. 4, pulls the wire 12 in the armoured flexible tubing back into position and the tension spring 23 which is shown anchored to the cut-away portion of the back of the figure of the traffic officer pulls up the bell-crank breaking the electric circuit leading to the lamp 15 and forces the left arm from the dotted position down to the natural position, thus terminating the left turn signal.

When it is desired to give the signal to stop, the foot brake is depressed which pulls down upon the coil spring 25, Fig. 1, and the wire 26 which leads through the armoured flexible tubing 27 and hollow bracket to the signal box and is attached to the middle bell-crank 24, Fig. 4, which has transverse leaves or bars 28, 29, 30, 31, which engage bell-cranks 4 and 17, Fig. 4, and pull them down with it and raise both pivoted arms of the figure of the traffic officer. As the bell-crank 24 depresses bell-cranks 4 and 17, the lower leg of 4 and 17 travels in a slot 39 in the metal bars connecting the pulling wires 3 and 12 with tension springs, thus preventing a backward thrust on those wires while the bell-cranks 4 and 17 pull down on wires 5 and 13 to raise both pivoted arms of the figure of the traffic officer. As the bell-crank 24 is pulled down it strikes an insulator attached to the top side of the charged spring leaf 8 before the bell-cranks 4 and 17 strike the insulators attached to spring leaves 7 and 18, thus preventing a contact being made by the bell-cranks raising the right and left arms as the bell-crank 24 depresses the charged spring leaf to make a contact with the spring leaf 33 which sends a current through the conductor 34 to the lamp 35 and projects through the red glass the word "Stop" in the front and rear and the letter "S" on the ends of the signal box giving out the signal "Stop".

As the foot brake is released, a tension spring attached to the bell-crank 24 and located between the tension spring 20 and the tension spring attached to the bell-crank 17 (not shown) pulls the wire in the flexible tubing back into position while the tension

springs in the body of the figure of the traffic officer pull up the bell-cranks 4 and 17 and force both pivoted arms of the figure of the traffic officer from the dotted position down to the natural position.

One advantage of my invention is that when signals are given they can be given as required by law before the vehicle starts to turn or stop, and the signal remains until it is released, allowing the driver to use both hands at the steering wheel in an emergency, thus avoiding disputes when accidents occur as to whether or not the proper signal was given, which sometimes happens when the rear driver did not see the hand put out and an emergency demanded that the driver use both hands at the steering wheel. Also the figure can be operated independent of the light, thus saving the battery in the daytime.

I also provide a locking device to hold the operating lever in the position to which it is shifted, which is shown at 40, Fig. 9, and consists of a spring made fast in the top of the operating box with both ends terminating in a bow in front of the slot in which the operating lever slides and which are bent to form a rest for the operating lever when it is in the central position. When the point of the lever 1, Fig. 9, is shifted either to the right or left into the respective dotted-line position, it passes beneath the downwardly bowed portion of the spring 40, lifting the latter during the first part of the movement. As the said point approaches the end of its travel, the spring settles down behind it, and thus yieldingly holds the lever 1 and the parts connected therewith in the position to which they have been moved. When the point of the lever 1 is thrown back to the central position the pull of the tension springs attached to the wires pulling on the released bell-crank is arrested by the top leg of the bell-crank in the operating box, striking against a rest 22, Fig. 9, and thus holds the operating lever in its central position.

The electrical circuits for operating the signal lights are shown in Fig. 2, in which 36 is the battery, 37 is the switch which when closed throws the current into the conductor 38 leading to the spring leaf 8. When the spring leaf 7 is depressed to contact with 8 a current flows through the conductor 9 to the lamp 10, and when the spring leaf 18 is depressed to form a contact with 8, a current flows through the conductor 14 to the lamp 15, and when the spring leaf 8 is depressed to form a contact with 33 a current flows through conductor 34 to the lamp 35. The tail light is shown at 39a. It is understood that the wiring is to be adapted to the kind of circuit used by the car installing my device, and that it is not necessary to utilize the signal lights during the day-

time, if it is desired to save the batteries, which can be done by opening the switch 37 and closing it when it is desired to use them.

5 I also provide a frame 41 on the front and rear sides of my signal box to hold the driver's license or other means of identification.

Having thus described my invention, what 10 I claim as new and desire to secure by Letters Patent is:

1. In a signal device for a vehicle a pair 15 of slotted slides, means operable from a remote point for separately moving said slides, springs for holding the slides in their normal positions, a bell-crank for each of said slides, each bell-crank having an arm extending into the slot of its respective slide whereby the bell-crank is rocked when its 20 slide is moved against the tension of its spring, a third bell-crank pivoted adjacent the first mentioned bell-crank and having means for engaging and rocking the latter bell-crank simultaneously, the arms of the 25 latter bell-crank then moving freely in the slots of their respective slides without moving the latter, and means for operating the said third bell-crank.

2. In a vehicle signaling device of the

character described, a plurality of signaling 30 elements, a support to which said elements are pivoted, a casing upon which said support is mounted, operating members extending from the respective signaling elements into the said casing, a plurality of bell-crank 35 cranks within the casing, there being a bell-crank for and connected with each of said operating members, operating means for and connected with each of said bell-crank for actuating the latter and the respective elements from a remote point, an additional bell-crank within the casing, means independent of the said operating means for actuating the said additional bell-crank, and means connected with the said additional 40 bell-crank and positioned to engage the first mentioned bell-crank when the additional bell-crank is operated, whereby the signaling elements are simultaneously operated.

3. A structure as specified in claim 2 in 45 which the casing contains a plurality of electric signal lamps and contact switches in circuits leading to said lamps, and means whereby said switches are selectively operated as the said bell-crank are actuated, 50 whereby the circuits leading to the lamps are selectively closed.

HENRY ALLES.
